PLIERS

Glenn W. Periman, Los Angeles, Calif.

Application September 14, 1944, Serial No. 553,970

6 Claims. (Cl. 81—51)

1

My invention relates to pliers and more particularly to such a tool that is adaptable to handling, trimming and cutting hot plastic material.

It is an important object of the invention to provide such a tool that will dissipate heat transmitted from the hot material to the pliers. The jaws of the pliers are also heated for neat cutting.

Other objects are to provide jaws for the pliers that will progressively pinch off the material from one side to the other, and to provide interchangeable jaws to more conveniently cut off any shape or form.

A further object is to provide a carefully adjustable stop that may be moved to limit the closing movements of the jaws to determined distances apart.

My invention also has for its objects to provide such means that are positive in operation, convenient in use, easily operated, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a side elevation of pliers embodying the foregoing objects.

Fig. 2 is a front elevation of said pliers, taken at right angles to Fig. 1.

Fig. 3 is a section taken on the line 3—3 of Fig. 2.

Fig. 4 is an end view taken on the line 4—4 of Fig. 2, in Fig. 2 looking in the direction of the arrows.

Fig. 5 is a section taken on the line 5—5 of Fig. 1 and

Fig. 6 is an enlarged section taken on the line 6—6 of Fig. 2.

Referring more in detail to the drawings, the reference numbers 6 and 7 designate the handles covered with insulating material, as probably best suggested in Fig. 3. The handles are preferably shaped as shown in the drawings, to conveniently fit the hand of the user. The backs of the handles carry fins 36 projecting outwardly therefrom and progressively increasing in length toward the gripping portion of the handles, progressively to increase the radiation therefrom. The fins in-

2

crease in outward extent from the one next the jaws toward the handles. Thickened fins 37 and 38 are arranged at opposite ends of the fin group to protect them from being broken off.

Shoulder member 8 and 9 are respectively connected with the handles 6 and 7 on the opposite side of the pivot bolt 10. The shoulder members 8 and 9 have dove-tailed faces 12 and 13 respectively, that fit in correspondingly shaped dove-tailed grooves in jaw members 14 and 15. The jaw members 14 and 15 are tapered at their ends, as shown at 16 and 17, and on their sides, as suggested at 18. Screws 19 and 20 respectively maintain the jaws 14 and 15 in their interlocked positions upon the shoulder members 8 and 9.

Means to limit the closing movements of the pliers comprises a block 21 slidable in a wedge-shaped groove 22 on the inner face of the handle 6. The block 21 has a similarly shaped wedge-shaped base 23 slidable in the groove 22. It will be noted that the bottom of the groove 22 and the opposed inner face 35 of the handle 7 converge to provide operating faces for the block 21. Actuating means for the block 21 consists of a bolt 24 mounted in a relatively fixed boss 25 also on the inner face of the handle 6. A snap ring 26 engages a circumferential groove 27 around the bolt 24 and a therewith opposed and complementary groove in the block, to prevent the removal of the bolt 24 after the ring 26 has snapped into place.

After the pliers have been moved to the most nearly closed position, determined by the block 21, a coil spring 28 tends to move the handles to an open position. The spring 28 is coiled around a pin 29 that is screwed into one of the handles, e. g., handle 6, and projects into a socket 30 in the other handle, to-wit, the handle 7. A lock nut 31 fastens the pin 29 in position. The spring 28 is disposed between the lock nut and the opposed face of the other handle. The adjacent end of the spring 28 may be spot welded to the lock nut 31 to prevent its falling from the pin 29, when the handles are apart.

It will be noted that the opposed faces 32 and 33 of the jaws 14 and 15 respectively, are not parallel. The purpose of this provision is to squeeze off surplus material when using the plier with hot substances, as plastics. It is preferable that these faces diverge outwardly from an abutting line 34 along one side of the jaws, when the jaws touch. Of course, if the wedge block 21 is moved further inward with respect to the angle between the handles, the jaws 14 and

15 will not touch even in their most nearly closing position.

In the use of my present pliers, they may be effectively used to handle, trim, cut, hold and bend work material, such as hot, bendable plastic. The fins 36 aid in radiating heat from the pliers into the surrounding atmosphere. The insulation on the handles 6 and 7 prevents heat that is not thus radiated, from burning the user's hands.

The purpose of having the block 21 prevent the pliers from entirely closing, is to avoid cutting entirely through soft, heated plastic material. The block 21 determines the limit of the closing movement of the pliers.

The coil spring 28 is compressed when the handles are moved towards each other, thereby aiding in separating the handles and opening the jaws when the handles are released. The construction of the jaws, heretofore described, permits their ready interchangeability. The dovetailed connection between the jaws and the shoulders 8 and 9 makes a firm connection for the jaws with the shoulders, but at the same time, permits ready removability by unscrewing the screws 19 and 20 and sliding the jaws up the incline provided by the faces 12 and 13. Other shapes of jaws having the present connecting means may be easily substituted for those shown.

Since the jaws are interchangeable, it is to be understood that various shapes of jaws may be employed, such as curved, right angle, round, square or any other desired shape to conveniently trim castings.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In pliers, handle and jaw members pivoted to each other, means to prevent the jaw members from coming together comprising a sliding block, the handle members having converging faces upon one of which the block is slidably and to which it is connected and the other of which the block engages in its adjusted positions, a boss on one of said converging faces and means adjustably carried by the boss and revolvably connected with the block to move the block along one of said faces and to maintain the block in its adjusted position.

2. In pliers, handle and jaw members pivoted to each other, the handle members having converging faces, a block arranged to prevent the jaw members from coming together, said block being slidably connected to one of said handle members, a boss on said handle member and screw means connected to said boss to adjust said block relative to the other handle member to maintain the jaw members different distances apart.

3. In pliers, handle and jaw members pivoted to each other, one of said handle members hav-

ing a dove-tail groove, means to prevent the jaw members from coming together comprising a sliding block having a dove-tail connection with the groove of said member and arranged to contact an opposed face of the other member, said opposed face converging with respect to the bottom of the groove, and screw means mounted upon the member carrying the block and connected thereto to move the block in opposite directions and to maintain the block in its adjusted positions.

4. In pliers, handle and jaw members pivoted to each other, and cooling fins on each of said handle members near the pivot thereof and between the pivot and the portion of the handle gripped by the user, to radiate heat tending to be conveyed from the jaws to the handles said fins progressively increasing in length toward the gripping portion of the handles, progressively to increase the radiation therefrom.

5. In pliers, handle and jaw members pivoted to each other, and cooling fins on the back of each handle, between the pivot and the portion of the handle gripped by the user, the fins increasing in size from the one nearest the pivot toward the gripping portions of the handle, and thickened, stronger fins at the ends of the series arranged to protect the other fins.

6. In a device of the character referred to, the combination of: handle members pivoted to each other intermediate their ends and provided with jaws at one end thereof, said jaws having substantially rectangular faces opposing each other and disposed in inclined relation with respect to each other to provide a gripping area at one side thereof and a progressive squeezing area at another side thereof a block longitudinally and slidably mounted on one handle member opposite the second handle member and engaging the other handle member, and means adjustably mounted on said first handle member and revolvably connected with the block to limit the inward movement of the handle members and consequently of the jaws.
